CONSTRUCTION FRAME

Filed Feb. 8, 1926

Inventor
WILLIAM M. GOLDSMITH,

Attorney

By Murray and Fugler

UNITED STATES PATENT OFFICE.

WILLIAM M. GOLDSMITH, OF CINCINNATI, OHIO, ASSIGNOR TO THE GOLDSMITH METAL LATH COMPANY, OF CINCINNATI, OHIO, A CORPORATION OF OHIO.

CONSTRUCTION FRAME.

Application filed February 8, 1926. Serial No. 86,801.

This invention relates to improvements in bucks for window and door frames.

An object of my invention is to provide a metal frame that can be readily and efficiently erected and to which a wood buck can be secured.

Another object of my invention is to provide a frame that can be manufactured completely at the factory.

Another object of my invention is to provide a metal buck to which metal lath may be secured when plaster or any other commutative partition is desired.

Another object of my invention is to provide a metal buck with which any other type of partition, such as gypsum block, clay tile, etc. may be used.

These and other objects are attained by the means described herein and disclosed in the accompanying drawings, in which:

Fig. 1 is a front elevation of my improved metal buck having secured thereto the wooden buck and metal lath.

Fig. 2 is a sectional view taken on line 2-2 of Fig. 1.

Fig. 3 is a sectional view taken on line 3-3 of Fig. 1.

Fig. 4 is a sectional view taken on line 4-4 of Fig. 1.

Fig. 5 is a view similar to Fig. 4, showing a modified method of attaching the wood buck to the metal buck.

Fig. 6 is a modified form of the metal buck.

The device of my invention comprises a metal frame or buck 10 having secured thereto the wooden buck 11.

The metal buck comprises T-shaped uprights 12 and 13 having a permanent brace 40 or header 14 intermediate its ends and defining the upper limit of the opening.

The uprights 12 and 13 comprise angles 15 and 16 having the back portion 17 of each angle secured together either by rivets or spot welding whereby a substantial T-shaped structure results.

At intervals throughout the leg 18 of the T-shaped uprights 12 and 13, perforations 19 are provided. Perforations 19 are utilized for securing metal lath 20 to the uprights 12 and 13 by passing a wire 21 through the said perforations 19 and through the openings in the open metal lath 20. The uprights extend from the floor 22 to the ceiling 23 of a building under construction.

Angles 24 having an elongated 55 perforation 25 formed in one side 26 thereof, are utilized for securing the upper end of the uprights to the ceiling 23. The elongated perforation affords a limited amount of adjustability when erecting the frame and is secured to the frame by any suitable means such as bolt and nut 27. The other leg 28 of the angle 24 is provided with a perforation 29 through which a wire, expansion bolt, or the like may pass for securing the angle 65 24 to the ceiling 23.

The arms 30 of the T-shaped uprights 12 and 13 are provided with perforations 31 through which nails 32 or any other securing means may pass for securing the wood buck 70 11 to the metal buck. The method of securing the wood buck to the metal buck just described is illustrated in Fig. 4. Fig. 5 illustrates another method of securing the wood buck to the metal buck which consists of 75 driving a nail or other securing means from the front of the wood buck into and between the angles 15 and 16 forming the T-shaped uprights.

The header 14 is made similar to the uprights 12 and 13 and comprises angles 34 and 35. Angles 34 and 35 are equal to the distance between the arms 31 of the uprights 12 and 13 plus the length of one leg of the angles 15 or 16. One leg 36 of each of the angles 34 and 35 is removed whereby a tongue 37 is formed which extends between the joined legs of the uprights 12 and 13. Rivets or any other securing means 38 extend through the joined legs of the uprights and through the tongue 37 of the header for securing the said header in position. In practice, the metal bucks are furnished having a second or temporary brace, shown in Fig. 1, in dotted lines at 39, near the lower edge 95 thereof in order to prevent distortion in handling. Before the wood buck is secured to the metal buck, this temporary brace 39 is removed intermediate the arms 31.

Although I have shown and described my improved buck as used for securing thereto metal lath, it is readily evident that any other partition may be built on either side of the joined legs of the T-shaped frame. It should also be understood that while I have illustrated my device as a door frame, it can be made into a window frame by simply inverting and securing a second brace 14 to the

uprights at the proper distance from the brace 14.

Fig. 6 is a modified form of a metal buck and comprises a single strip of material bent upon itself whereby a stem 40 is formed. The ends 41 and 42 of the strip are bent at right angles to the stem 40 which form the arms of the T-shaped frame. The arms 41 and 42 and the stem 40 may be provided with perforations for securing thereto the metal lath and wood buck.

To the wood buck is attached the door or window trim. The wood buck also forms a ground for the plaster.

15. What I claim is:

1. A door frame comprising a pair of vertical uprights, each upright comprising a pair of associated angle-irons of L-shape cross section, each angle-iron of each pair thereof comprising each upright, having a leg disposed adjacent a leg of its associated angle-iron and the second legs of said associated angle-irons extending in alignment and in opposite directions whereby a table like structure is provided on each upright, and a way is formed extending inwardly of said table and between the said adjacent legs of the angle-irons and into which way fastening means may be projected and wherein 20 said fastening means may be frictionally retained, and means for holding the uprights in a spaced, substantially parallel relationship.

2. A door frame comprising a pair of vertical uprights, each upright comprising a pair of associated angle-irons of L shape cross section, each angle-iron of each pair thereof comprising each upright, having a leg disposed adjacent a leg of its associated angle-iron and the second legs of said associated angle-irons extending in alignment and in opposite directions whereby a table like structure is provided on each upright, and a way is formed extending inwardly of 35 said table and between the said adjacent legs of the angle-irons, a header comprising a pair of angle-irons related together as are the angle-irons of each upright related to one another, the header angle irons having 40 each a leg projecting beyond the other angle-iron and such projecting legs being disposed at opposite ends of said header, the said projecting legs being received, one in the way formed between the angle-irons of one upright, and the other in the way formed between the angle-irons of the second upright.

3. A door frame comprising a pair of vertical uprights, each upright comprising a pair of associated angle-irons of L shape cross section, each angle-iron of each pair thereof comprising each upright, having a leg disposed adjacent a leg of its associated angle-iron and the second legs of said associated angle-irons extending in alignment 50 and in opposite directions whereby a table

like structure is provided on each upright, and a way is formed extending inwardly of said table and between the said adjacent legs of the angle-irons and into which way fastening means may be projected and wherein 55 said fastening means may be frictionally retained, and means for holding the uprights in a spaced, substantially parallel relationship and means for fixedly mounting the frame between a floor and a ceiling structure.

4. A door frame comprising a pair of vertical uprights, each upright comprising a pair of associated angle-irons of L shape cross section, each angle-iron of each pair thereof comprising each upright, having a leg disposed adjacent a leg of its associated angle-iron and the second legs of said associated angle-irons extending in alignment and in opposite directions whereby a table like structure is provided on each upright, and a way is formed extending inwardly of 60 said table and between the said adjacent legs of the angle-irons, a header comprising a pair of angle-irons related together as are the angle-irons of each upright related to one another, the header angle-irons having each a leg projecting beyond the other angle-iron and such projecting legs being disposed at opposite ends of said header, the said projecting legs being received, one in the way formed between the angle-irons of one upright, and the other in the way formed between the angle-irons of the second upright, and means for fixedly mounting the frame 65 between a floor and a ceiling structure.

5. A metal construction frame comprising a pair of uprights having an upper and a lower end, a header intermediate the ends of the uprights and securing the uprights in spaced relation, and a temporary brace secured to the uprights at their lower ends to prevent distortion of the frame while in 70 transportation.

6. The combination with a supporting structure of a metal construction frame comprising an upright, of an angle-iron, each leg of which is provided with an elongated perforation, means carried by the upright and received in one perforation in one 75 leg of the angle-iron for adjustably securing the angle-iron and the upright upon one another and means insertable in the opening in other leg for adjustably securing the angle-iron to the support, the elongated perforations permitting relative adjustment of the angle-iron, the construction frame and the supporting structure.

7. A header comprising a pair of angle-irons, each comprising a pair of associated diverging legs, each angle-iron having one of its legs disposed with its outer flat face immediately adjacent and in substantial parallelism with a similar face of the other angle-iron, whereby the four legs of the two 80

- angle-irons project in three directions from a common apex of said angle-irons, the said immediately adjacent and parallel legs of said angle-irons each projecting at one end 5 beyond its associated angle-iron leg, the projecting end of one angle-iron leg disposed at one end of the header, and the projecting end of the second angle-iron leg disposed at the opposite end of the header.
- 10 8. A construction unit comprising a pair of T shape parallel members having the table surfaces of each opposed one to the other, and a pair of connecting members extending between the parallel members and fixedly retaining said members in spaced relationship, whereby a substantially rectangular frame is provided and to which frame a wooden door buck structure may be attached.
- 20 9. A construction unit comprising a pair of spaced, substantially parallel members of T shape cross section, the table surfaces of said members being opposed one to the other, whereby flat supporting surfaces are 25 provided interiorly of the frame and to which surfaces a wooden buck structure may be attached, a T shape header fixed to and between the said two members, the table surface of the header adapted to receive a 30 wooden buck member connecting a wooden buck structure supported by the said two

members, and a detachable cross brace connecting the parallel members for co-operation with the header member in retaining the parallel members in parallelism until 35 after said unit shall have been secured in a fixed position in a building.

10. In a construction frame the combination of a metal buck having a substantial T-shaped cross section and a wood buck secured thereto. 40

11. In a construction unit the combination of a metal buck comprising uprights and a cross brace, the uprights and cross brace having a substantial T-shaped cross section 45 and provided with perforations, a wood buck secured to the metal buck, and means insertable through said perforations for securing the metal and wood bucks together. 50

12. A metal construction unit comprising 55 uprights each having an upper and a lower end, a header intermediate the ends of the uprights, and a detachable temporary brace secured between the uprights intermediate the ends thereof and adjacent the lower ends of the uprights for preventing distortion of the frame prior to installation thereof.

In testimony whereof, I have hereunto subscribed my name this 28th day of January, 1926.

WILLIAM M. GOLDSMITH.
